ATTORNEY

UNITED STATES PATENT OFFICE

JOSEPH FRED MERKEL, OF ROCHESTER, NEW YORK, ASSIGNOR TO GENERAL RAILWAY SIGNAL COMPANY, OF ROCHESTER, NEW YORK

CONTACT FINGER FOR RELAYS

Application filed October 8, 1926. Serial No. 140,375.

This invention relates in general to relays, and refers more particularly, to a contact finger for relays such as used, for example, in railway signaling.

5 In one usual form of contact fingers, the contact tip is fixed to a resilient arm that is united to the finger, and this resilient arm is flexed on each operation of the relay whereby a permanent set is soon given to the arm 55 which disturbs the adjustment of the relay, decreases the pressure between contacts and increases the necessary travel of the finger before initial contact. Such a permanent set 10 which cannot be readily corrected, and thus in practice the life of a relay is materially shortened.

It is also usual, in relays, to use relatively thick material, of rectangular cross section, for the contact fingers in order to obtain the requisite strength, but this thickness of material 20 results in material deformation of the finger under varying temperature conditions such as relays are subjected to in practice.

With the above and other considerations in mind, it is proposed, according to this invention, to make a contact finger formed of 25 two rigid members formed of light material and having channel sections, the two members being pivoted to each other and relatively biased by an adjustable spring.

30 Among the objects of this invention, are, to simplify the construction, increase the efficiency, and prolong the useful life, of devices of the character in question.

Further objects, purposes, and characteristic features, will appear as the description progresses, reference being had to the accompanying drawings, showing, solely by way of example, one form of the invention. In the drawings:—

40 Fig. 1 is a top plan view of a detached contact finger constructed in accordance with this invention.

Fig. 2 is a side elevation of the finger, shown connected to an operating member, and with parts broken away.

45 Fig. 3 is a bottom plan view of the detached contact finger.

Fig. 4 is a sectional view of a detail.

50 Fig. 5 is a section on line 5—5 of Fig. 2, viewed in the direction of the arrows.

Referring to the drawings, the contact finger shown therein comprises two main parts, a carrier member 1 and a pivoted member 2 pivoted to the member 1 by mounting it on an arm 3 consisting of a cut out portion of the member 1 bent up at right angles thereto as shown. The arm 3 has a strip 4 cut from each edge and bent away from the body of the arm 3, in a curved formation, as best shown in Fig. 2, to form bearings for the pivoted member 2 which is slotted to pass over the upper end of arm 3 and is held thereon against the strips 4, by a wire 5, passing through a hole in the arm 3, above the pivoted member, and bent around such arm 65 in a general S shape (Fig. 1).

The members 1 and 2, as shown, are formed with a channel section, of thin material, an aluminum alloy for example, and preferably by stamping, the channel section giving the members the necessary rigidity, while the thin material used avoids any material deformation of the same due to temperature changes such as those to which relays are subjected, when in use.

70 The carrier member, is furnished with a plurality of apertures 6, variously shaped and spaced to permit of fastening it to various operating means. In the particular form illustrated, the carrier member is shown bolted to a pivoted armature 7 of a D C relay, but it can of course, be used in connection with any desired type of relay.

75 The end of the carrier member is furnished with an aperture 6' for connection to a lead-in wire or pigtail, unless this connection be made at a different point as described below.

80 The carrier member 1 has its free end bent slightly downward, as at 8, and then forward, as at 9, the part 9 being received in an aperture 10 in a downwardly projecting end 11 on the member 2, while the part 8 is received in an aperture 12 in a spring arm 13 riveted at 14 to the member 1 and having riveted to 85 it a contact tip 15 of highly conductive material, such as coin silver or the like.

85 At the outer end of pivoted member 2 is riveted an inverted U-shaped contact 16 of coin silver or other highly conductive ma- 100

terial. The contact tips 15 and 16 constitute respectively the back and front contacts of the device.

A flexible wire 17, preferably of stranded copper, is fastened, as by soldering it, at 18, to the front contact 16, is then looped through the pivoted member 2 at 19, passed through a downwardly extending end 20 on the spring arm 13, and has its other end soldered to a connecting ring 21 adapted to be clamped to a terminal post of the relay in which this contact finger is to be used.

This pivoted member 2, at its inner end, has riveted to it, a threaded bolt 22 passing down through an opening 23 in the member 1, and about this bolt opening 23 the material is cut back to form three arms 24 which are bent downwardly at right angles to the member 1 to form a cup for receiving a washer 25. The threaded end of the bolt has a longitudinal groove 26, and a spring receiving cup 27 is slidably received on a bolt, and has an inwardly projecting lug 28 received in the groove to thus prevent rotation of the cup 25 on the bolt.

A nut 29 is threaded onto the bolt and has a plurality of saw slots 30 in its inner face, for receiving an upstanding lock finger 31 integral with, and pressed out of the material forming, the cup. A compression coil spring 32 is sleeved on the bolt and bears at its two ends on the washer 25 and cup 27. The cup and nut 27, 29, together with the spring 32, form an effectual locking means, the finger 31 on the cup preventing rotation of the nut 29 since the lug 28 on the cup prevents the cup from rotating on the bolt, while the spring 32 holds the cup and nut in locking contact with each other.

The spring 32 operates to bias the pivoted member 2 and its front contact 16, away from the end of member 1 with the part 9 of member 1 bearing against the lower edge of aperture 10 therein, (Fig. 5) while the spring arm 13 is adjusted to be normally biased away from the member 1, with part 8 of member 1 bearing against the upper edge of aperture 12.

It is thus clear that movement of carrier member 1 about its fixed end in an upwardly or a downwardly direction, between usual front and back fixed contacts, will operate to press the front or back contact 16 or 15, toward the member 1, until motion is limited by the apertures 10 or 12, against the tension of spring 32 or spring arm 13.

At any time, with the construction just described, the tension of spring 32 can be easily adjusted by screwing of the nut 29 on the bolt 22, after having first pulled the lock finger 31 out of engagement therewith, to thus vary the tension on the arm 2 carrying the movable front contact 16 without, at the same time, affecting the proper initial position of such contact.

The above rather specific description of a device embodying this invention, is given solely by way of illustration, and is not intended, in any manner whatsoever, in a limiting sense. Obviously, this invention can assume many different physical forms, and is susceptible of various modifications, and all such forms and modifications are desired to be included by this invention, as come within the scope of the appended claims.

Having described my invention, I now claim:

1. In a relay contact finger, a carrier member, a front contact, a back contact, an arm for each contact fastened to the carrier member, and a projection on the carrier member passing through motion limiting parts on the arms.

2. In a relay contact finger, a carrier member, a front contact, a back contact, an arm for each contact fastened to the carrier member, a closed loop on each said arm receiving one end of the carrier member, the arms being normally biased away from the carrier member with the carrier member bearing against one edge of each closed loop.

3. In a relay contact finger, a carrier arm, a cut-out upstanding integral strip on the arm, a part at each edge of the strip being bent away from the strip to form curved bearings, a contact carrying arm pivoted on the strip and resting against the curved bearings, and means to hold the contact arm on its pivot.

4. In a relay contact finger, a carrier arm, a struck up integral strip on the arm, a part at each edge of the strip being bent away from the strip to form curved bearings, a contact carrying arm pivoted on the strip and resting against the curved bearings, and a wire passing through the end of the strip above the carrying arm and bent to hold the contact arm on said strip.

5. In a relay contact finger, a carrier member, a rigid contact arm pivoted to the member, a threaded stem fixed to the contact arm and passing through the carrier member, a longitudinal groove in the threaded part of the stem, a cup slidable on the stem, a lug on the cup projecting into the groove, a plural slotted nut on the stem, a lock finger on the cup arranged to fit into any one of the nut slots, and a spring sleeved on the stem between the cup and the carrier member.

6. In a relay contact finger, a carrier member, a rigid contact arm pivoted to the member, a threaded stem fixed to the contact arm and passing through the carrier member, a longitudinal groove in the threaded part of the stem, a cup slidable on the stem, a lug on the cup projecting into the groove, a slotted nut on the stem, a lock finger on the cup arranged to fit into any one of the nut slots, a spring sleeved on the stem between

the cup and the carrier member, and integral lugs struck out from the carrier member around the stem aperture for receiving one end of the spring.

5 In testimony whereof I hereby affix my signature.

JOSEPH FRED MERKEL.
